(57) **CLAIM**

The ornamental design for a composter, as shown and described.

DESCRIPTION

FIG. 1 is a front and top left side perspective view showing the new design for a composter;

FIG. 2 is a front and top right side perspective view thereof; FIG. 3 is a rear bottom and left side perspective view thereof;

FIG. 4 is a rear bottom and right side perspective view thereof;

FIG. 5 is a front view thereof;

FIG. 6 is a rear view thereof;

FIG. 7 is a left side view thereof;

FIG. 8 is a right side view thereof;

FIG. 9 is a top plan view thereof;

FIG. 10 is a bottom plan view thereof;

FIG. 11 is a front and top left side perspective view showing the new design for a composter with its lid in the open position;

FIG. 12 is a front and top right side perspective view thereof; FIG. 13 is a rear bottom and left side perspective view thereof;

FIG. 14 is a rear bottom and right side perspective view thereof;

FIG. 15 is a front view thereof;

FIG. 16 is a rear view thereof;

FIG. 17 is a left side view thereof;

FIG. 18 is a right side view thereof;

FIG. 19 is a top plan view thereof;

FIG. 20 is a bottom plan view thereof;

FIG. 21 is a front and top left side perspective view showing the new design for a composter with its lid in the open position and a bucket exploded out therefrom;

FIG. 22 is a front and top right side perspective view thereof;

FIG. 23 is a rear bottom and left side perspective view thereof;

(Continued)

FIG. 24 is a rear bottom and right side perspective view thereof;
 FIG. 25 is a front view thereof;
 FIG. 26 is a rear view thereof;
 FIG. 27 is a left side view thereof;
 FIG. 28 is a right side view thereof;
 FIG. 29 is a top plan view thereof; and,
 FIG. 30 is a bottom plan view thereof.
 The broken lines shown in the drawings depict portions of the composter that form no part of the claimed design.
